SPOOLING OR REELING APPARATUS

Herman Zarafu, New York, N. Y., assignor to
 Elevator Supplies Company, Incorporated, New
 York, N. Y., a corporation of New Jersey

Application July 24, 1937, Serial No. 155,353

11 Claims. (Cl. 242—25)

This invention relates to spooling or reeling mechanism of wire drawing apparatus or the like and provides improvements therein.

The general construction and operating characteristics of wire drawing and spooling machines may be summarized as follows: The machine comprises a plurality of dies of progressively smaller size and a capstan after each die, the capstans being so driven as to have progressively higher peripheral speeds occasioned by the elongation of the wire in passing through each die. For the purpose of avoiding breakage of the wire, the machines are so designed that the peripheral speed of each capstan-drum is somewhat less than the peripheral speed of the preceding capstan-drum plus the elongation of the wire in passing through the preceding die, so that there is a continual "slip" of the wire on the capstan-drums through the machine. That is, while the wire is pulled forward all the time, its speed is less than the peripheral speed of each of the capstan-drums around which it passes by the amount of slip which occurs. The amount of slip is governed by the difference between the actual, or designed, peripheral speed of each capstan-barrel, and the required peripheral-speed to correspond to the speed of the wire on leaving the preceding capstan-barrel plus the elongation in passing through the preceding die, and also by the pull on the wire after it leaves the last capstan.

The capstans are driven at a constant speed, and the requisite of proper operation is that the wire should be pulled from the final capstan by the spooling mechanism at a speed approximately but not fully equalling the peripheral speed of the final capstan, to thereby admit of the "slip" within the wire drawing machine hereinbefore referred to.

With wire drawing apparatus as constructed heretofore, there are limitations to the speed at which wire may be drawn, especially fine wire. For example the same percentage of slip in a machine having a capstan peripheral speed of 5000 feet per minute as in a machine having a capstan peripheral speed of 1000 feet per minute, would produce five times the amount of rub or friction between the capstan surface and the wire. That is, with 10% slip, the wire would slip 500 feet per minute in a machine having a capstan peripheral speed of 5000 feet per minute, as against 100 feet per minute in a machine having a capstan peripheral speed of 1000 feet per minute. At the present time machines are being designed to run with a capstan peripheral speed of 10,000 feet per minute. Assuming that

10% slip on a capstan having a peripheral speed of N feet per minute is the maximum allowable to insure against wire "burning" (also against grooving of the capstan surface), at higher and higher capstan peripheral speeds the percentage of slip must be less and less, in order to avoid "burning" and grooving. However, the percentage of slip in a wire drawing machine is not a definite or invariable amount; it is a variable amount around a mean, due to a number of factors the primary one of which is the changing take-up speed of the spooling or reeling means or other means exerting a positive pull on the wire. Moreover slip ahead of the reeling or positive pulling means cannot be eliminated in machines for drawing fine wire, because if the reeling means took-up the wire faster than it is paid-off by the capstan the tension on the wire would rise to the breaking-point.

Moreover, the velocity factor of masses in motion and hence the force, or impact, of such masses is greatly increased at the higher wire-drawing speeds. Hence, the desirability, or even the practical necessity, especially in high speed machines for drawing fine wire, of avoiding the use of parts which in the operation of the machine would produce impacts on the wire.

The present invention provides a novel and improved spooling or reeling mechanism and one which is especially adapted for use as a part of, or conjointly with a wire drawing machine.

It provides a mechanism of the character referred to, which operates to regulate the slip of the wire within a narrow range, and which is very sensitive to changes in the amount of slip.

Furthermore, it provides a mechanism of the character described, in which the wire is not subjected to the shock or impact of a contacting mass or body; that is, the mechanism avoids the use of wire contactors or "feelers", which bodies have the effect of their masses being greatly augmented by velocity in high speed machines, and hence exert considerable and detrimental forces or impacts on the wire during the operation of the mechanism at very high speeds. It further provides mechanism of the character referred to capable of being used when operated at very high speeds without burning and with a reduced liability of breaking the wire. It further provides a mechanism of the character described in which a diminishment of the speed of rotation of the spool or shaft is so effected as to be closely responsive to successive increases in the diameter of the wire coil during spooling and in which the running of the spooling mechanism inclusive of

such adjustments or changes of speed of rotation is relatively steady.

The invention further provides a mechanism of the character described which may be readily reset for successive spooling or reeling operations, which is durable, of relative simplicity, and reliable in operation.

An embodiment of the invention is illustrated in the accompanying drawings, wherein:

10 Fig. 1 is a view in side elevation of a wire drawing machine comprising a reeling or spooling mechanism according to the present invention.

15 Fig. 2 is a transverse vertical sectional view of a spooling or reeling mechanism as shown at the left of Fig. 1.

15 Fig. 3 is a diagrammatic view illustrating the electrical arrangement and relations of the electrical parts of the mechanism shown in Fig. 2.

Referring to said drawings, numeral 10 designates the wire drawing part of the machine, and 20 12 the spooling or reeling mechanism. The wire drawing part of the machine comprises a series of wire drawing dies 13 and capstans 14, 15, and has the operating characteristics hereinbefore described.

25 The spooling or reeling mechanism 12 comprises a spindle or other suitable means 18 for supporting and rotating a shaft or spindle S, the spindle being driven to rotate the spool. When the spooling mechanism forms a part of a wire drawing machine, the spindle 18 is advantageously driven from a part of the wire drawing mechanism, as by a sprocket 19, which is driven by a sprocket chain (or another suitable means) from a driven part of the wire drawing machine 10. The sprocket 19 may be, as here shown, fixed on a shaft 20 on which the final capstan 15 is fixed.

30 The spindle 18 is mounted on or forms a part of a shaft 25, and a change-speed device 30 is arranged in the mechanism for driving the shaft 25 and spindle 18. The change-speed device 30 is of a type which provides a wide variation in the speed of rotation of shaft 25, so that coils of considerable thickness can be wound.

35 The change speed device comprises two pulleys 32, 33, each of variable diameter, and a belt 35 passing around the two pulleys 32, 33. Pulley 32 comprises two disks 36, 37, and pulley 33 comprises two similar disks 38, 39. Each of these disks, 36—39 has an inclined friction surface, opposite pairs of disks forming a V-shaped surface with which the belt 35 makes contact. One of the disks of the pulley 32, as the disk 36, is fixed on shaft 26, and the opposite disk 37 is movable longitudinally of the shaft 26 as indicated at 41, so as to vary the effective diameter of the pulley 32 on which the belt turns. The disks 38, 39 of pulley 33 may be mounted on a countershaft 44, and one of these disks, as the disk 39, is fixed on the shaft 44, and the other disk 38 is movable longitudinally of the shaft 44 as indicated at 46, to vary the effective diameter of the pulley 33. As here shown, the shaft 25 is driven from the countershaft 44 through gears 48, 49.

45 Numeral 50 designates a shifter operating on the diagonally opposite longitudinally movable disks 37, 38. The shifter 50 comprises a bar 51 having arms 53, 54 which hold sleeves 56, 57 which serve to move the movable disks 37, 38 toward the opposite disk, when the bar 51 is moved 50 in the proper direction. The effect of the belt 35 is to normally tend to move the movable disks 37, 38 away from the opposite disk.

55 When the disk 37 of pulley 32 is shifted away from the disk 36, the opposite disk 38 is simul-

taneously shifted toward the disk 39. This simultaneously decreases the effective diameter of pulley 32 and increases the effective diameter of the pulley 33. By such an operation of the shifter 50, as just described, the speed of rotation of the shaft 25 and spindle 18 is decreased, and, at the same time the peripheral speed of the spool or bobbin and of the coil of wire building thereon is decreased. It will be understood that by such decreases of the speed of rotation of the shaft 25 and spindle 18 through the change speed mechanism 30, the peripheral speed of the coil of wire winding on the spool S, is successively adjusted to the peripheral speed of the final capstan 15, and thereby a peripheral speed of the coil of wire building on the spool S, approximating the peripheral speed of the final capstan 15, is maintained.

60 The shifter 50 is moved in a direction to decrease or increase the speed of rotation of the shaft 25 and spindle 18 by suitable means 60, as the electric motor here shown. The motor 60 turns the shifter 50 through suitable means, as for example a worm 62, worm gear 63, shaft 65, worm 66 and worm gear 67. The worm gear 67 turns 65 or is provided with a threaded sleeve 68 which engages a screw 69 fixed to the sleeve 66. When the threaded sleeve 68 is turned in one direction, it operates to move the disk 37 of pulley 32 toward the disk 36, and simultaneously, through the arms 53, bar 51, arm 54 and sleeve 57, to move the disk 38 of pulley 33 away from the disk 39, thereby increasing the speed of rotation of shaft 25, as previously described. When the threaded sleeve 68 is moved in the opposite direction, the disk 37 of pulley 32 is moved away from the opposite disk 36, and simultaneously the movable disk 38 of pulley 33 is moved toward the disk 39, through the parts previously described.

65 The motor 60 is intermittently energized to 40 change the speed of rotation of the shaft 25 and spindle 18 in the proper sense to maintain a peripheral speed of the coil winding on the spool S to closely approximate the peripheral speed of the final capstan 15, and to maintain the amount 45 of slip of the wire on the final capstan 15 within a narrow range, by the means about to be described. The degree of slip on the final capstan 15 also determines the degree of slip of the wire on the other capstans 14 of the wire drawing machine. In apparatus for spooling or reeling very fine wire, especially, the mechanism may be so contrived and operated as to confine the amount of slip to a narrow range, in which the minimum amount of slip approaches, zero slip of the wire 55 on the final capstan 15.

70 The means for energizing the motor to change the speed of rotation of shaft 25 and spindle 18, and to regulate the amount of slip of the wire on the final capstan 15 within a narrow range, 60 comprises a free running pulley 70, and a contact device 75. The free running pulley 70 may be, as here shown, mounted on an extension 76 of the shaft 20 on which the final capstan 15 is fixed, and is rotated by the moving wire which 65 runs around it in passing to the spool S, and the wire imparts to the said free-running pulley 70 a peripheral speed substantially equal to the speed of the wire itself. The contact device 75 is mounted adjacent the pulley 70 on the shaft 70 extension 76.

75 The contact device 75 comprises a brush 78, which may be, as here shown, carried on the free running pulley 70, and electrically connected with a contact ring 79 on shaft 20 by a ground through 78

a pulley 70, shaft extension 76 and shaft 20; see Fig. 3. Spaced contacts 81, 82 in the path of movement of the brush 78, are provided on a hub 84 fixed on the shaft extension 76, and these 5 contacts are connected respectively to the insulated contact rings 87, 88 through insulated wires 90, 91.

As shown in Fig. 3, the motor 60 is a three-phase motor connected to a three-phase wire-10 system through relays 120, 121, the action of which is controlled by the contact device 75 in a secondary low-tension electrical circuit.

When brush 78 rides on contact 81 current flows from a battery 122, solenoid 123 of relay 15 120, contact ring 87, wire 90, brush 78, grounded ring 79 and back to the battery 122 through the ground. The energization of solenoid 123 closes the relay 120, and current flows from the three-phase line to the phase windings 1, 2, 3 of the 20 motor 60 in the sequence 1-3-2 or counter-clockwise. This would cause motor 60 to reduce the effective diameter of pulley 32, increase the effective diameter of pulley 33 and diminish the speed of rotation of spindle 18 of the reel or 25 spool.

When brush 78 rides on contact 82 current flows from the battery 122, solenoid 124 of relay 121, contact ring 88, wire 91, brush 78, ground ring 79 and back to the battery through the 30 ground. The energization of solenoid 124 closes the relay 121, and current flows from the three-phase line to the phase windings 1, 2, 3 of the motor 60 in the sequence 2-3-1, or clockwise, or in the reverse direction to that in which motor 35 60 turns when relay 120 is actuated. This acts on the pulleys 32, 33 so as to increase the speed of rotation of the spool-spindle 18.

In stringing the machine, the wire is wound one or more times around the final capstan 15, 40 as may be required, then around a free running pulley 93 (when, as here shown, the pulley 70 is mounted on the shaft extension 76), then around the free running pulley 70 one or more times, as may be desired or required, and then if desired, 45 over a roller 95 on a cushion arm 96, and thence to the spool S.

Before passing to the spool the wire may be passed through the guide 99 of a traversing device 100 by means of which the spirals of wire are built up into the coil on the spool S in the desired manner. As here shown, the traversing device 100 comprises a reciprocatory frame 101 which carries the guide 99, and reciprocatory movement may be imparted to the frame 101 55 through a cam 103 in a drum 105 driven from the shaft 25 through a pinion 106 and a gear 107.

The free running pulley 70 is made with a smaller circumference or periphery than that of the final capstan 15.

Suppose that it is desired to operate the machine with a slip of the wire on the final capstan 15 with a minimum of approximately one percent. If the final capstan 15 has a peripheral speed of 5000 feet per minute, and has a circumference of 15.708 inches (diameter of 5''), the circumference of the free running pulley 70 would be made 15.55 inches (diameter of 4.95''), so that it would have a peripheral speed of 4950 feet per minute or one percent less than the peripheral speed of the final capstan 15. With a one percent slip of the wire on the final capstan 15, the wire would travel on the final capstan 15 and on the free running pulley 70 at about the same speed, and the final capstan 15 and the free running 5 pulley 70 would rotate at about the same speed.

If there was less than one percent slip of the wire on the final capstan 15, the wire would pay-off faster, and consequently cause the free running pulley 70 to rotate faster than final capstan 15. The free running pulley 70 would then creep 5 ahead of the final capstan 15 and bring the brush 78 into contact with contact segment 81, closing the circuit to motor 60, and cause it to turn in a direction to reduce the effective diameter of the pulley 32 and increase the effective diameter 10 of the pulley 33, and thereby reduce the speed of rotation of the shaft 25, and the peripheral speed of the wire winding on the spool S. The reduction in the peripheral speed of the wire winding on the spool S would allow more slip on 15 the final capstan 15, which slip, when it exceeded one percent, would result in the wire paying-off of the final capstan 15 somewhat slower than previously, and this would result in the free running pulley 70 being turned somewhat slower than previously. The speed of rotation of the final capstan 15 would then exceed the speed of rotation of the free running pulley 70, and contact segment 81 would move away 20 from the brush 78 (on the free running pulley 25 70) and break the circuit to the motor 60. The brush 78 on free running pulley 70 would then drift toward the opposite contact segment 82. If, before the brush 78 made contact with the contact segment 82, the diameter of the coil 30 building on the spool S increased, the peripheral speed of the wire winding on the spool S would increase, and at the same time the amount of slip of the wire on the final capstan would decrease, the paying-off speed of the wire from the final capstan 15 would increase and likewise the speed 35 of rotation of the free running pulley 70 would increase. Then or shortly after, the speed of rotation of the free running pulley 70 would increase with relation to the speed of rotation of 40 the final capstan pulley 15, and the brush 78 on the free running pulley 70 would again move or creep toward the contact segment 81, and when the brush 78 makes contact with the segment 81, the motor 60 would be again energized, and the 45 sequence of operations just described would be repeated.

If, however, following the operation of the motor 60 to decrease the speed of rotation of the shaft 25 (and thereby the peripheral speed of 50 the wire building on the coil on the spool S), the free running pulley 70 should continue to rotate at a slower speed than the final capstan 15, the brush 78 carried by the slower rotating free running pulley 70, would make contact with the contact segment 82, and thereby establish a circuit 55 to the motor 60 which is the reverse of the circuit established through the contact segment 81. Thereupon the motor 60 would be caused to turn in a direction the opposite to that previously described. That is, the motor 60 would be turned in a direction to increase the effective diameter of the pulley 32 and decrease the effective diameter of the pulley 33, the effect of which would be to increase the speed of rotation of the shaft 25, spindle 18, and the peripheral speed of the coil on the spool S. Thereby the wire would be wound on the spool faster, turn the free running pulley faster, reduce the slip on the final capstan 15, and immediately, or within a short 70 interval, cause the free running pulley 70 to run ahead of the final capstan 15, and carry with it the brush 78 thereon so as to break contact between the brush 78 and the contact segment 82, and stop the motor 60.

When the peripheral speed of the wire winding on the coil increases (as by enlargement of the diameter of the coil) the operation as described would again ensue: That is, the free running pulley 79 would run ahead (faster) than the final capstan 15, until the brush 78 on the free running pulley 79 again makes contact with the contact segment 81, establishing a circuit to the motor 60, and causing it to turn the pulleys 32 and 33, in the manner previously described, to decrease the speed of rotation of the spindle 18 and the peripheral speed of the coil on the spool S. By a proper design of the amount of change effected by the running of the motor 60, through the electric circuit established between the brush 78 and one or the other contact segment 81, 82 (and also by adjusting the spacing of the said contacts 81, 82) the departure from the amount of slip 81 of the wire on the final capstan 15 may be adjusted within a very narrow range. Also, in this way the running of the machine may be steadied, and the peripheral speed of the wire winding on the coil maintained nearly constant.

25. After the winding of the wire on the spool S has been completed, the machine is stopped, and the spool removed and replaced by another. The pulleys 32, 33 are then reset to a position where the initial peripheral speed of the wire winding 30 on the spool S corresponds to a peripheral speed of about one percent less than the peripheral speed of the final capstan 15. In the example given above, where the peripheral speed of the final capstan 15 is 5000 feet per minute, the pulleys 32, 33 of the change speed device 30 would 35 be set to provide an initial winding-on speed of the wire on the spool S of 4950 feet per minute.

The initial setting of the pulleys 32, 33 of the change speed device 30 may be facilitated by 40 means of an indicator 110 comprising a calibrated scale 112 and a pointer 114 attached to the bar 51 of the shifter 50. The setting of the pulleys 32, 33 may be effected by closing a circuit to the motor 60, through a push button 115 and maintaining it closed and the motor running, until pointer 114 indicates that the pulleys 32, 33 have been moved to the position required 45 to provide the desired initial winding-on speed of the wire on the spool S. A second push button 116 may be provided for manually running the motor in reverse. The brush 78 is at the same time set at a position about midway between the contact segments 81, 82.

A description of the operation and of the apparatus has been incorporated in the foregoing 55 description.

The invention may receive other embodiments than that herein specifically illustrated and described.

60. What is claimed is:

1. In combination, a driven capstan and a free-running pulley, around each of which a loop or loops of a wire runs, means for pulling wire from said capstan, and means associated with said free-running pulley operative upon a difference in speed of rotation between said capstan and said free running pulley for regulating the speed at which said wire-pulling means pulls wire from said capstan.

70. 2. In combination, a driven capstan and a free-running pulley, around each of which a loop or loops of a wire runs, means for pulling wire from said capstan, and means associated with said free-running pulley for regulating the speed at which said wire-pulling means pulls wire from

said capstan, said regulating means comprising an electrical contact rotatable at the same speed as said capstan, an electrical contact rotatable at the same speed as said free-running pulley, an electric motor device and electrical connections between said contacts and said motor-device. 5

3. In combination, a driven capstan and a free-running pulley, around each of which a loop or loops of a wire runs, said free-running pulley having a periphery different from that of said capstan, means for pulling wire from said capstan, and means associated with said free-running pulley for regulating the speed at which said wire-pulling means pulls wire from said capstan comprising an electrical contact rotatable at the same speed as said capstan, an electrical contact rotatable at the same speed as said free-running pulley, an electric motor device and electrical connections between said contacts and said motor-device. 10

4. In combination, a driven capstan and a free-running pulley, around each of which a loop or loops of a wire runs, means for pulling wire from said capstan, and means associated with said free-running pulley for regulating the speed at which said wire-pulling means pulls a wire from said capstan, said regulating means comprising two sets of contacts, one set of spaced contacts and the other set an intermediate contact, one set of said contacts being rotatable at the same speed as said capstan and the other set being rotatable at the same speed as said free-running pulley, an electric motor device and electrical connections between said contacts and said motor-device. 20

5. In combination, a driven capstan and a free-running pulley, around each of which a loop or loops of a wire runs, said free-running pulley having a periphery different from that of said capstan, means for pulling wire from said capstan, and means associated with said free-running pulley for regulating the speed at which said wire-pulling means pulls wire from said capstan, said regulating means comprising two sets of contacts, one a set of spaced contacts and the other set an intermediate contact, one set of said contacts being rotatable at the same speed as said capstan and the other set being rotatable at the same speed as said free-running pulley, an electric motor device and electrical connections between said contacts and said motor-device. 30

6. Spooling or reeling apparatus, comprising a spool or reel spindle, a driven capstan paying-off wire to a spool or reel on said spindle, and means for driving said spindle including means for regulating the speed of rotation of said spindle so that the peripheral speed of the coil of wire building on the spool or reel is maintained at approximately the peripheral speed of said capstan and the slip of the wire on said capstan is regulated, said latter means comprising a change-speed device and means comprising a wire-driven part for producing changes in said change-speed device. 40

7. Spooling or reeling apparatus, comprising a spool or reel spindle, a driven capstan paying-off wire to a spool or reel on said spindle, and means for driving said spindle including means for regulating the speed of rotation of said spindle so that the peripheral speed of the coil of wire building on the spool or reel is maintained at approximately the peripheral speed of said capstan and the slip of the wire on said capstan is regulated, said latter means comprising a change-speed device and means for producing 7

changes in said change-speed device comprising a free-running wire-driven pulley, an electric motor, and a circuit thereto comprising a contact rotatable at the same speed as said capstan and a contact rotatable at the same speed as said free-running pulley.

5. Apparatus according to claim 7, wherein said change-speed device comprises a variable diameter pulley having a shiftable part, and means actuated by said motor for shifting said part.

10. Apparatus according to claim 7, wherein said change-speed device comprises two variable diameter pulleys, each having a shiftable part, a shifter for moving said shiftable pulley parts in opposite directions, and means actuated by said motor for moving said shifter.

15. Apparatus according to claim 7, further

comprising means for resetting said change-speed device to an initial position following the completion of the winding of a coil and before beginning the winding of another.

11. Apparatus according to claim 7, wherein said change-speed device comprises a variable diameter pulley having a shiftable part, a shifter for moving said shiftable pulley part, and means actuated by said motor for moving said shifter, and further comprising means for resetting said change-speed device to an initial position following the completion of the winding of a coil and before beginning the winding of another, and means for indicating the setting of said change speed device comprising an indicating part 10 mounted on said shifter. 15
